UNITED STATES PATENT OFFICE.

WILLIAM P. BROWN, OF ZANESVILLE, OHIO.

PLOW-HANDLE.

SPECIFICATION forming part of Letters Patent No. 252,722, dated January 24, 1882.

Application filed December 10, 1881. (Model.)

To all whom it may concern:

Be it known that I, WM. P. BROWN, a citizen of the United States, resident at Zanesville, in the county of Muskingum and State 5 of Ohio, have invented a new and valuable Improvement in Plow-Handles; and I do hereby declare that the following is a full, clear, and exact description of the construction and operation of the same, reference being had to 10 the annexed drawings, making a part of this specification, and to the letters and figures of reference marked thereon.

Figure 1 of the drawings is a representation of a perspective of my plow - handle brace. 15 Fig. 2 is a side view, and Fig. 3 is a view showing the brace attached to a plow.

This invention has relation to the braces for the handles of plows, cultivators, seeders, and other implements needing such supports; and 20 it consists in the construction and novel arrangement in the upper end of the brace of a curved slot having a shouldered bend in its intermediate portion for engagement with the bolt which connects the handle thereto, as 25 hereinafter set forth.

In the annexed drawings, the letter A designates the beam of the plow or other implement, to which the lower end of the brace B is connected by means of a bolt, C, passing through 30 a perforation or slot, D, in said brace.

E represents the handle, to which the upper end of the brace is connected. This end of the brace is formed with a curved slot, F, having a shouldered or supporting bend, G, in its intermediate portion. In forming this bend the shoulder H or bearing is made on that wall of 35 the slot which is nearest the beam A. Sometimes a second intermediate bearing may be

made in the slot, as indicated at K. The slot is usually made in hook form, having a rearward extension, L, and a forward and downward extension, N, as indicated in the drawings. The handle is connected to the brace by means of a bolt, P, which passes through the curved slot and is adjustable therein. The 45 bolts C and P, whereby the brace is connected to the beam and handle, are provided with nuts and washers, so that they can be easily loosened and tightened.

The stem S of the brace may be made single, 50 or it may be forked so as to embrace the beam. When the nuts are loosened a little the handle can be readily adjusted to the height required; or it can be lowered alongside the beam, so that it will take up but little room, comparatively, in storage or transportation.

Having described this invention, what I claim, and desire to secure by Letters Patent, is—

1. The combination, with the handle E, beam 60 A, and bolts C and P, of the handle-brace B, having a curved slot in its upper end, formed with an intermediate shouldered bend or bearing, substantially as specified.

2. The handle-brace B, having at its upper 65 end the curved slot F, formed with an intermediate shouldered bend, G, a rear extension, L, and a forward and downward extension, N, substantially as specified.

In testimony that I claim the above I have 70 hereunto subscribed my name in the presence of two witnesses.

WILLIAM P. BROWN.
